UNITED STATES PATENT OFFICE.

MATTHEW J. WELLING, OF CHICAGO, ILLINOIS, ASSIGNOR TO O-CEDAR CORP'N., A CORPORATION OF ILLINOIS.

MOP.

Application filed April 13, 1927. Serial No. 183 282.

This invention relates to a mop and concerns itself primarily with the supporting frame for the mop swatch and the method of attaching the mop swatch thereto.

It is an object of this invention to provide a mop that may be constructed in a simple and economical manner from sheet metal and to provide a novel method for attaching the mop swatch to the mop head, in such a way as to form a cushioning and protecting outer edge for the mop head to prevent the mop head from marring and scoring furniture in its use.

Other and further important objects of this invention will become apparent from the following description and appended claims.

On the drawings:

Figure 1 is a top plan view of a completed mop.

Figure 2 is a sectional view taken on line II—II of Figure 1.

Figure 3 is a fragmentary elevational view of the mop swatch before attachment to the mop head.

Figure 4 is a sectional view taken on line IV—IV of Figure 3.

Figure 5 is a fragmentary side elevational view of the finished mop.

Figure 6 is a sectional view taken on line VI—VI of Figure 5.

Figure 7 is a sectional view taken on line VII—VII of Figure 6.

As shown on the drawings:

In making a mop embodying the principles of this invention, a flat piece of sheet metal is suitably stamped to provide a head, indicated as a whole by the reference numeral 1, having a central raised plane portion 2, an inner peripheral groove 3 and an upstanding peripheral flange 4 extending from said

groove and formed with an inwardly extending concave face 5. Said head 1 may be of any desired shape but is here illustrated as triangular in outline. To the intermediate raised portion 2 there is secured a strap 6 having an aperture 7 therein. Both the raised portion 2 and the strap 6 are suitably stamped to provide a recess 8 in which the lower arcuate end 9 of a handle socket 10 is adapted to be secured for pivotal movement.

A mop swatch indicated as a whole by the reference numeral 11 is formed by securing to a relatively wide band 12 of flexible material, such as canvas, mop strands 13. The mop strands 13 are secured to the lower portion of the band 12 by means of threads 14 sewed

around the mop strands intermediate their ends to form a loop 15 of the strands adjacent the upper lines of the sewing.

The mop swatch is now attached to the mop head 1 by laying the upper free portion of the band 12 over the peripheral flange 4 in such a manner that the band 12 extends into the groove 3. A triangular-shaped ring 16, formed of sheet metal to fit within the groove 3, is next inserted into said groove 3 over the band 12 and clamped therein by frictional engagement with the edges of said groove 3. The respective adjacent ends 17 and 18 of the band 12 are secured together by means of a clip member 19, formed of sheet metal and stamped to conform with the contour of the peripheral flange 4. Said clip member 19 is further provided with outwardly struck prongs 20 adapted to extend through suitably arranged apertures 21 in the peripheral flange 4 to secure said clip member 19 to said flange 4, with the band 12 lying therebetween.

It should be noted that the loop 15 of the mop strands 13 lies within the concave face of the peripheral flange 4 and together with the overlying band 12, serve as a cushion and protective covering for the flange 4 to prevent marring and scoring the furniture should the mop come into contact therewith during use.

It will be appreciated that owing to the material used and the simplicity of the method employed for making the mop, that the same may be made at very slight cost when produced on a large scale and the scope and spirit of the appended claims.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A mop comprising a mop head having a peripheral upturned edge, a mop swatch including a band having a free portion extending over said upturned edge to cover the same, and a clamping member engaging said free portion of the band below said edge to secure said swatch to said head.

2. A mop comprising a mop head stamped from sheet metal and provided with an upstanding peripheral flange having an outer inwardly concave face, a flexible band, mop strands secured to a portion of said band

intermediate the ends of said strands, and a ring member adapted to clampingly secure the free portion of said band to said mop head, whereby said band covers said flange and the mop strands are crowded into the concave face of said flange to provide a cushion therefor.

3. A mop comprising a head including an upwardly extending peripheral portion, a 10 mop swatch disposed about said portion including a band having a free portion extending over the top of said peripheral portion and down alongside the inner surface of said peripheral portion, said peripheral portion of said head being shaped to define a groove 15 for receiving said mop swatch, and means for securing said free portion of the band to said head whereby said swatch is held in said groove.
4. A mop comprising a head including an upwardly extending peripheral flange portion and a mop swatch disposed about said portion and connected to said head, said swatch including a band formed into substantially a channel shape between the sides 25 of which said peripheral portion extends, mop strands secured to the outer side of said band, and means for securing the inner side of said band to said head.

5. A mop comprising a head including an

upwardly extending peripheral flange portion and a mop swatch disposed about said portion and connected to said head, said swatch including a band formed into substantially a channel shape between the sides 35 of which said peripheral portion extends, mop strands secured to the outer side of said band, said inner side of said band being bent inwardly over the top of said head, and a clamping ring on top of said bent portion of 40 the band for securing the mop swatch to the mop head.

6. A mop comprising a head including an upwardly extending peripheral flange portion and a mop swatch disposed about said portion and connected to said head, said swatch including a band formed into substantially a channel shape between the sides of 45 which said peripheral portion extends, mop strands secured to the outer side of said band, said inner side of said band being bent inwardly over the top of said head, and a clamping ring on top of said portion of the band adapted to frictionally engage said peripheral portion of the head to secure the 50 mop swatch thereto.

In testimony whereof I have hereunto subscribed my name at Chicago, Cook County, Illinois.

MATTHEW J. WELLING.
